UNITED STATES PATENT OFFICE.

AUGUST PETER, OF CINCINNATI, OHIO.

GARMENT-SUSPENDING DEVICE.

988,809.

Specification of Letters Patent. Patented Apr. 4, 1911.

Application filed September 24, 1910. Serial No. 583,648.

To all whom it may concern:

Be it known that I, AUGUST PETER, a subject of the Emperor of Germany, residing at Cincinnati, in the county of Hamilton 5 and State of Ohio, have invented new and useful Improvements in Garment-Suspending Devices, of which the following is a specification.

This invention relates to a garment suspending device, and its object is to provide an ever-ready article of this character which is simple of construction, inexpensive of construction adapted to be conveniently carried in the pocket, and susceptible of 15 application to supports of various kinds to suspend a garment or article therefrom.

The invention consists of the features of construction, combination and arrangement of parts, hereinafter fully described and 20 claimed, reference being had to the accompanying drawings, in which:—

Figure 1 is a perspective view of a garment suspending device embodying my invention. Fig. 2 is a rear elevation of the 25 same. Fig. 3 is a front elevation. Fig. 4 is a side view illustrating the mode of use of the device. Fig. 5 is a detail view, showing the impaling pins disposed between the arms to enable the device to be carried in 30 the pocket.

In carrying my invention into practice, I provide a garment suspending device 1 preferably made from a single length of spring wire, nickel-plated or otherwise covered to 35 prevent it from rust and to give it an ornamental appearance.

As shown, the wire is bent to provide a pair of approximately parallel longitudinally curved arms 2, which are of equal 40 length and are connected at one end by an intermediate portion of the length of wire, which is bent to provide a suspending hook 3. The hook 3 projects from the rear side of the lower ends of the arms, and from the 45 upper ends of said arms the extremities of the wire are bent forwardly, downwardly and rearwardly to provide a pair of impaling pins 4 having pointed or sharpened free ends 5. The extremities of the wires 50 so bent to provide the impaling pins are curved into substantially loop-form, and extend diagonally to and downwardly upon the outer sides of and across the arms 2, the

pointed ends 5 of said impaling pins projecting beyond the rear sides of said arms 55 above the suspending hook 3.

The wire of which the device is formed permits the impaling pins to be sprung forwardly so as to project the pins 5 between the arms 2, as shown in Fig. 5, in which position said points will be partially guarded or shielded by the arms and the hook 3, allowing the device to be conveniently carried in the pocket without liability of the points catching into the lining of the pocket or 60 injuring the fingers of the operator in inserting and withdrawing the device from the pocket. When it is desired to use the articles, the impaling pins may be sprung forwardly to project on the outer sides of 65 the arms 2 for use, as will be readily understood.

In the use of the device, the hook 3 is engaged with any suitable portion of the garment or article to be suspended, such as the 75 suspending strap 6 of a coat 7, the rear portion of the suspending member brought into proximity to a support, such as a board, wooden post or like support, and the upper ends of the impaling pins pressed rearwardly, so as to force the points 5 of said pins into the support, by which the device 80 will be held firmly in position to suspend the article. When it is desired to release the article, the loop-shaped members of the 85 device may be engaged between the thumb and finger and an outward pulling pressure exerted to withdraw the points of the pins. In such manner, the suspending device may be used to support the garment from convenient articles of various kinds—even from 90 brick walls, as the points of the impaling pins may be forced into the mortar between the edges of the bricks.

It will be seen from the foregoing description that a handy and convenient suspending device for the purpose set forth is provided, and that resilient loops formed by the portions constituting the impaling pins enables said pins to be readily manipulated in 100 the manner described.

Having thus described the invention, I claim:—

1. A garment suspending device comprising a single length of wire bent to form a 105 pair of arms, a hook connecting the arms at

one end, and impaling pins extending from the opposite ends of the arms and crossing the same at a point above the hook.

2. A garment suspending device comprising a single length of wire bent to provide a pair of longitudinally curved arms, a hook extending rearwardly from the lower ends of the arms, and impaling pins extending forwardly and downwardly from the upper ends of the arms in the shape of resilient

loops, said pins having their free ends extending diagonally across the arms and terminating in pointed extremities arranged above the hook.

In testimony whereof I affix my signature 15 in presence of two witnesses.

AUGUST PETER.
